UNITED STATES PATENT OFFICE.

WILLIAM JUDSON SMITH, OF ST. PAUL, MINNESOTA.

TRUCK.

1,405,168.

Specification of Letters Patent.

Patented Jan. 31, 1922.

Application filed May 8, 1920. Serial No. 379,730.

To all whom it may concern:

Be it known that I, WILLIAM JUDSON SMITH, a citizen of the United States, residing at St. Paul, in the county of Ramsey and State of Minnesota, have invented certain new and useful Improvements in Trucks, of which the following is a full, clear, and exact description, such as will enable others skilled in the art to which it appertains to make and use the same.

This invention relates to trucks, and with respect to its more specific features to trucks for street railway cars.

An object of the invention is to provide 15 an improved truck which is relatively light in weight, and which is relatively cheap in first and maintenance costs.

Another object is to provide an improved truck which is capable of ready dis-assembly 20 and assembly for repairs, or for other purposes.

Another object is to provide an improved journal-box construction which is capable of ready positioning on the axle and easy 25 attachment or detachment from the truck pedestals.

A further object is the provision of a 30 truck fitted with an improved braking mechanism and structure which avoids wear on the truck wheels and has other advantageous features.

Other objects will be in part obvious and in part pointed out hereinafter.

The invention accordingly consists in the 35 features of construction, combinations of elements and arrangement of parts which will be exemplified in the construction hereinafter set forth, and the scope of the application of which will be indicated in the 40 following claims.

In the accompanying drawings forming part of this specification wherein an illustrative embodiment of the invention is shown,

45 Figure 1 is a plan view of a truck embodying the invention;

Fig. 2 is a side elevational view of the same, certain parts being shown in section more clearly to disclose the invention;

50 Fig. 3 is a detailed fragmentary sectional view showing the bolster and spring suspension;

Fig. 4 is a top plan view, and

Fig. 5 an end elevation of the lower section of one of the journal-boxes;

Fig. 6 is a top plan view, and

Fig. 7 an end elevation of the upper section of one of the journal boxes;

Fig. 8 is a sectional view on the line 8—8 of Fig. 6 looking in the direction of the 60 arrow;

Fig. 9 is a sectional view on the line 9—9 of Fig. 6 looking in the direction of the arrow;

Fig. 10 is a side elevation of the upper 65 half of the journal box looking from the left of Fig. 7;

Fig. 11 is a top plan view, and

Fig. 12 a side elevation of one of the truck 70 pedestal castings;

Fig. 13 is a sectional view taken on the line 13—13 of Fig. 12;

Fig. 14 is an end elevation of the truck 75 pedestal casting looking from the left of Fig. 12;

Fig. 15 is an end elevation of the same looking from the right of Fig. 12;

Fig. 16 is a detailed sectional view taken on the line 16—16 of Fig. 15, and

Fig. 17 is a detailed sectional view taken 80 on the line 17—17 of Fig. 12.

Referring now for a more detailed description of the illustrative embodiment of the invention shown in the drawing particularly to Figs. 1, 2 and 3, the truck is 85 designated generally by reference numeral 1, 2 designates the wheels, 3 the axles, 4 the truck bolster, 5 the truck bolster center bearing, 5^a the side roller bearings, and 6 the truck frame. The truck frame comprises 90 transverse end pieces 7 secured in any approved manner as by gusset plates 8 to the truck side frame members 9. These side frame members may be of any approved design, but preferably the diamond arch bar 95 type is used as shown in the drawing. Transom members 7' also extend transversely of the truck frame and are connected to the truck frame members by suitable gusset plates. The side frame comprises an arch 100 bar 10, inverted arch bar 11 and pedestal tie-bar 12, and each of these bars is secured to the bolster guide-bars or truck columns 13 and to the truck pedestals 43, as will be more fully described hereinafter. Located 105 inside of the wheels 2 are journal boxes 15 which are divided upon horizontal lines to form upper and lower sections 15^a and 15^b respectively. These journal boxes are adapted to be movably secured to the truck pedestals by means which will be presently fully 110 described.

Load stresses are transmitted from the bolster 4 to the truck frame through any suitable means; preferably double elliptic bolster springs 16 are employed, upon the 5 upper member of which the ends of the bolster rest. For this purpose suitable bearing blocks 17 are provided on the bolster spring and the lower member of said spring is provided with a bearing block 18 which 10 rests upon spring plank bearings 19 of spring plank 20. From the spring plank bearing 19 the load stresses are transmitted through suitable nuts 21 to swing hangers 22 and through pivotal connections thereof 15 to the truck frame. As shown in the illustrative embodiment, the spring plank bearing is pivotally supported by the nuts 21 which have suitable projections engaging in corresponding depressions on the under side 20 of the spring plank bearing. These nuts are screwed to the lower ends of the swing hangers 22 which are secured at their upper ends to a shaft 23 extending transversely of the bolster. The ends of the shaft 23 are supported by bearing blocks or castings 24 25 mounted on the arch bar 10 of the truck frame and having downwardly extending portions engaging and secured to the truck columns 13. From the truck side frame 30 members the load stresses are transmitted through the journal boxes to the wheels.

As will be clear from Figs. 1 and 2, the journal boxes 15 are spaced on the truck axles inside the wheels, and are connected 35 through the truck pedestals as will later be described in detail. The journal box construction is substantially the same at all four corners of the truck, and is shown in detail in Figs. 4 to 9 inclusive. As shown, 40 each box is divided into upper and lower sections, each comprising an integral casting, the two sections being bolted together when in cooperative relationship upon the axle. For this purpose apertures 24, 25 and 45 26 are formed in the upper half of the box, and corresponding apertures 24', 25' and 26' are formed in the lower section. The aperture 24 is internally threaded, as shown in Fig. 5, to receive the threaded lower end of 50 a stud bolt 24^a which is passed downwardly through the aperture 24 in the upper section of the journal box. The apertures 25 and 26 are similarly internally threaded to receive the threaded ends of stud bolts 25^a 55 which are passed upwardly through the apertures 25' and 26' in the lower section. By this means the two sections of the journal box are held securely in cooperative relationship and may be readily disassembled should 60 occasion require. Suitable dustguards are provided at the ends of the journal box, and for this purpose the upper casting is supplied with a recess or slot 27 at the inner side thereof, and 65 with a similar slot 28 at the outer side. The

lower section or casting is provided with complementary slots 27' and 28', and when the two sections are secured together the respective slots cooperate to form channels to accommodate the dustguard members which 70 are shown at 29 and 30 in Fig. 9. Suitable journal bearings or brasses 30^a may be fitted to each section of the journal box, and these brasses may be faced, if desired, with a layer of babbitt 30^b or similar antifriction metal. 75

The upper section of each journal box is constructed to form a seat for a truck pedestal, each pedestal resting upon a cushion 31 of suitable material such as rubber, as indicated in Fig. 2, this cushion being suitably seated in a recess on the upper surface of the upper section. On the face towards the bolster the upper section is supplied with lateral projections 32 and 33 extending outwardly from the section and towards each other so as to form a dovetailed slot 34. This slot is adapted to cooperate with a similar slot on the lower section of the journal box to form a seat for the truck pedestal as will be more fully described hereinafter. 80 85 Also each upper casting is formed on the far side of the bolster with a depression 35 forming a seat for the nose portion of the truck pedestal.

The lower section of each journal box is 90 also supplied on the side adjacent the bolster with lateral projections 36 and 37 extending outwardly therefrom and towards each other and forming a dovetailed slot 38 similar to the slot 34 described above. The 100 slot 38 is adapted to cooperate with the slot 34 to form a seat for the truck pedestal as above mentioned. A lateral pocket 39 extends from the side of each lower section of the journal box and is adapted to receive 105 packing and lubricating grease. This grease pocket is located at the side of the journal box away from the bolster so that the same is readily accessible for inspection, or for the insertion of grease or packing. The grease 110 pocket may be conveniently provided with a cover 40 which is held in place by means of stud bolt 41 extending through an opening in the cover, the threaded lower end thereof extending into an internally threaded aperture 42 at the bottom of the pocket. 115

At each end of the truck side frame a truck pedestal 43 is secured in position as by bolts 44 and 45 passing through the pedestal and the bars of the side frame. The arch bar 10 and inverted arch bar 11 pass over the top of the truck pedestal as shown in Fig. 2, and the pedestal tie-bar 12 passes thereunder, the bolt 44 passing through the whole to secure the parts in assembled relationship. 120 125 For this purpose also the bolt 45 passes through the arch bars and the nose of the pedestal casting.

The detailed construction of the illustrative embodiment of the truck pedestal 43 is 130

shown in Figs. 11 to 17. As there shown this pedestal comprises an integral casting having a generally horizontally disposed body portion 46, a generally vertically disposed portion 47 and a downwardly extending nose portion 48, stiffening flanges 49 being preferably secured at its upper end to a depending similar flanges 50 on the vertical portion. As shown in Fig. 17 the flanges 50 partially 5 form the walls of an aperture 51 through which the bolt 44 passes. At its upper portion this aperture is entirely surrounded by the metal of the pedestal as shown in Fig. 16, and at its lower end the aperture extends 10 through an outwardly projecting flange 52 as shown at 51 in Fig. 12. Also as shown in Fig. 17, the vertical portion of the pedestal is provided with inclined webs 53 terminating in inwardly extending flanges 54, these 15 flanges and webs being so disposed in relation to each other as to form a section of the pedestal which is substantially trapezoidal or dovetailed in cross section, and corresponds in shape and dimensions approximately 20 to the slots 34 and 38 in the journal boxes.

The under portion of the horizontal section 46 of the pedestal casting is provided with a recess in which is seated the resilient 25 cushion 31 when the parts are in assembled relationship, as is clearly shown in Fig. 2. The nose portion 48 corresponds in shape and dimensions with the recess 35 in the wall of the upper section of the journal box, said 30 nose portion seating in said recess when the parts are in assembled relationship so as to form a firm connection between the journal box and pedestal.

As shown at 55 and 56 in Fig. 1, each axle 40 of the truck may be equipped with a suitable driving motor. As the motors with their attachments to the truck and means for transmitting power to the axle form no part of the present invention, further description 45 of them is considered unnecessary.

In the operation of the improved truck construction thus far described, the truck pedestals 43 are securely held in position at the ends of the side frames of the truck 50 by bolts 44 and 45. Each pedestal movably engages its associated journal box, the vertical dove tailed section of the pedestal engaging in the aligned dovetailed slots 37 and 38 of the upper and lower section of the 55 journal box, the horizontal portion seating against the cushion 31 on the upper face, and the nose portion seating in the recess 35 of said upper section. By this means the truck frame is securely but removably held in assembled 60 relationship with the journal box and associated parts. Should it become necessary to remove the axle for any purpose it is only necessary to raise the truck frame and the pedestals will slide from engaging 65 relationship with the journal boxes, and the

axles with wheels and motors may then be rolled from beneath the frame. When the parts are to be assembled, the reverse operations are followed.

It will be particularly noted that the truck 70 thus provided requires a relatively small amount of material in its manufacture and is correspondingly light and cheap in manufacturing cost. Trucks constructed according to this design weigh only from one-half 75 to one-third the weight of the standard brake-shoe truck in use at the present time for similar purposes. The truck is quickly assembled and disassembled, little work being required for this purpose, and repairs 80 and adjustments are readily made.

This design of truck is particularly adapted for use on passenger street cars or for passenger cars used in light trains for street or other railway use, and is especially adapted 85 to be used on cars making up light trains, as a motor and a trailer.

In order to simplify the construction and reduce the weight of the truck, a special braking mechanism has been designed, and 90 to this end the ordinary brake-shoes taking against the periphery of the truck wheels have been discarded. In the embodiment of this improved braking means shown in the drawing, a single brake-drum 60 having a 95 relatively large braking surface on its periphery is rigidly mounted on each axle 2 so as to rotate therewith. This drum is supplied with a friction brake band 61 which is arranged to engage with the periphery of 100 the drum throughout nearly 360° thereof. Improved means for applying and releasing said brake band is also provided. As shown in Figs. 1 and 2 the brake band operating 105 means comprises a bell crank 62, the short arm of which is pivoted to a bracket 63 mounted on the upper end of the brake band, the other or long arm being connected to the brake actuating mechanism. Pivotedly connected at one end to the elbow of the 110 bell crank lever is a link 64 slidably supported in an opening in the angularly disposed flange 66 of a bracket or casting 65, the latter being suitably mounted in position adjacent the truck column 13 upon one of the 115 transoms 7' and truck side frame 9. The other end of the link 64 extends through an opening in a bracket or casting 67 secured to the other end of the brake band 61, and is held in cooperative relationship with said 120 bracket by a nut threaded on the end of said link. A spiral spring 68 surrounds the lower end of said link 64, at one end abutting the brackets 67 and at the other end abutting the angularly disposed flange 66, whereby 125 the brake band is yieldingly held in released position. It will be noted that this construction allows the brake band to extend nearly around the brake drum, thus providing a maximum of braking effort for a minimum 130

of weight and size of the parts of the braking mechanism.

Each brake band is supported at one side by a depending link 69 secured by a set screw 5 in an elongated slot formed in a bracket 70 which is riveted or otherwise suitably secured to the brake band. This link 69 is suitably secured at its upper end to a depending flange of the cross piece or sill 7.

10 Each bell crank lever 62, 62' is operated by suitable means to apply the brake, and as shown in the present embodiment, this means comprises a brake rod 71 extending forwardly as shown in Fig. 1 to a suitable 15 hand or power braking mechanism. This braking mechanism may be of any standard construction, forms no part of the present invention, and need not be further described. The other end of the brake rod is pivotally 20 secured to an equalizing bar 72 intermediate the ends thereof, preferably at its center of length. At one end this bar is fitted with a clevis 73 which is pivotally connected thereto and bifurcated at one end to receive 25 the upper end of the long arm of the bell crank lever 62 to which it is pivotally connected as at 74. The opposite end of the clevis 73 is supplied with a lug 74' having an aperture therein to receive the end of a 30 coiled tension spring 75, the opposite end of which is adjustably secured by a threaded eye bolt 75' to a bracket 76 mounted on the transom 7'.

The other end of the equalizing bar 72 is 35 also fitted with a clevis 77 which is pivotally connected thereto, and a flexible member such as a chain 78 is attached at one end to said clevis extending approximately in a horizontal direction around a horizontally 40 disposed sheave mounted in a bracket 79 on the end piece 7, the end of the backwardly extending portion being connected to a clevis 80 at the upper end of the long arm of the bell crank lever 62'. Also connected 45 at one end to the clevis 80 is a second coiled tension spring 81, the opposite end of which is connected by suitable adjustable means to a bracket secured on the transom 7'. This adjustable means may conveniently comprise 50 a threaded eye bolt passing through said bracket and having nuts thereon to hold and lock the same in adjusted position.

While a single brake drum of comparatively large dimensions is disclosed as being 55 mounted on each axle, it is obvious that more than one brake drum may be employed, if desirable. It is found in practice, however, that a single brake drum of comparatively large dimensions is preferable as it provides 60 a lighter, more compact and more economical braking mechanism.

The operation of the braking mechanism which will be obvious from the above description may be briefly described as follows:

65 When a brake is to be applied, a pulling

stress is applied to the brake rod 71, and this stress is transmitted to the bell crank lever 62 through the equalizing bars 72 and the connections therefrom as described above. Thus the bell crank levers will be moved 70 against the resistance of compression springs 68 to pull the adjacent ends of the brake band together to the drum and apply the brake. When the braking force is removed from the brake rod 71 the braking elements 75 are urged to off position by means of the releasing springs 75 and 81, and this action is also assisted by the expansion of band releasing springs 68.

Having described my invention, what I 80 claim as new and desire to secure by Letters Patent is:

1. In a truck, in combination, trussed side frame members, commercial end frame members connecting said side frame members, 85 a pedestal secured to one of said side frame members, a journal box for the truck axle disposed inwardly from the truck wheels, and means for connecting said pedestal to said journal box by vertically slidable engagement therewith.

2. In a truck, in combination, a side frame member including a pedestal, an arch-bar and an inverted arch-bar secured to the upper portion of said pedestal and a pedestal tie-bar secured to the lower portion thereof, 95 a journal box spaced inwardly from the truck wheel, and means whereby said pedestal removably engages said journal box.

3. In a truck, in combination, a side frame 100 member including a pedestal, an arch-bar and an inverted arch-bar secured to the upper portion of said pedestal and a pedestal tie-bar secured to the lower portion thereof, a journal box and connecting means for connecting said pedestal to said journal box by vertically sliding engagement therewith.

4. In a truck, in combination, a side frame member including a pedestal, an arch-bar and an inverted arch-bar secured to the 110 upper portion of said pedestal and a pedestal tie-bar secured to the lower portion thereof, a journal box disposed inwardly from the truck wheels, and dovetail connecting means for connecting said pedestal to said journal 115 box.

5. In a truck, in combination, a side frame member including a pedestal, an arch-bar and an inverted arch-bar secured to the upper portion of said pedestal and a pedestal tie-bar secured to the lower portion thereof, 120 a journal box disposed inwardly from the truck wheels, and means for effecting a sliding connecting engagement between said journal box and said pedestal.

6. In a truck, in combination, a side trussed frame member disposed inwardly from the truck wheels, transverse frame members connecting said side frame members, a pedestal for said side frame member, a journal box, 125

- and means whereby said pedestal engages said journal box for connecting the latter to the former, and a cushion between said journal box and said pedestal.
- 5 7. In a truck, in combination, a trussed side frame member, a cast metal pedestal member having vertical and horizontal portions detachably connected to the truss members of said side frame member, a journal box disposed inwardly from the truck wheels, and means whereby said pedestal member slidably engages said journal box to positively connect the former to the latter.
- 10 8. In a truck, in combination, a side frame member, a pedestal having a vertical portion with projecting edges and a horizontal portion, a journal box having grooves in one face thereof in which said edges slide for connecting said journal box and pedestal, and 20 a cushion between said journal box and said horizontal portion.
- 15 9. In a truck, in combination, a side frame and a bolster swingingly connected thereto, a pedestal for said side frame, a journal box disposed inwardly of the truck wheels and means whereby said pedestal engages said journal box for removably connecting the former and the latter.
- 25 10. In a truck, in combination, side frame members disposed inwardly of the truck wheels, a bolster swingingly connected to said side members, a pedestal for said side frame members, journal boxes and means for removably connecting said pedestals and 35 journal boxes.
- 30 11. In a truck, in combination, side frame members disposed inwardly of the truck wheels and including truck columns and pedestals, arch-bars secured to the tops and bottoms of said truck columns and to the tops of said pedestals, and tie-bars secured to said columns and pedestals, a bolster swingingly connected to said side frame members, a journal box and means for removably connecting said journal box to said pedestal.
- 35 12. In a truck, in combination, side frame members disposed inwardly of the truck wheels and including truck columns and pedestals, arch-bars secured to the tops and bottoms of said truck columns and to the tops of said pedestals, and tie-bars secured to said columns and pedestals, a bolster swingingly connected to said side frame members, a journal box, and means whereby said journal box slidably engages one of said pedestals to removably connect the same.
- 40 13. In a truck, in combination, a rectangular truck frame having trussed side members, journal boxes disposed inwardly from the truck wheels, pedestals slidably engaging said journal boxes to secure the former to the latter whereby the frame may be lifted from the journal boxes, and braking mech-
- anism including a brake drum spaced inwardly of said side frame members.
- 45 14. In a truck for railway cars, in combination, a truck frame having trussed side members and end members connecting the ends of said side members, unitary pedestals secured to said side members and having vertically disposed portions, journal boxes disposed inwardly from the truck wheels and having slots therein for sliding connection with the vertical portions of said pedestals providing means whereby said pedestals and said journal boxes are rigidly held in assembled relationship while at the same time permitting the pedestal to be raised from engagement with said journal box.
- 50 15. In a journal box for railway trucks, in combination, upper and lower sections and aligned dovetailed recesses in said sections.
- 55 16. In a journal box for railway trucks, in combination, upper and lower sections, aligned dustguard recesses in said sections at both ends thereof, and aligned recesses in said sections for securing said journal box to a truck.
- 60 17. In a journal box for railway trucks, in combination, upper and lower sections, aligned dovetailed recesses in said sections and dustguard recesses at both ends of said sections.
- 65 18. In a journal box for railway trucks, in combination, upper and lower sections divided substantially on horizontal lines, means for securing said sections in cooperative relationship, said means including a bolt passing downwardly in said upper section threaded into said lower section, and a bolt passing upwardly in said lower section and threaded into said upper section, and aligned recesses in said sections for securing said journal box to a truck frame.
- 70 19. In a journal box for railway trucks, in combination, upper and lower sections divided substantially on horizontal lines, means for securing said sections in cooperative relationship, said means including a bolt passing downwardly in said upper section and threaded into said lower section, and a bolt passing upwardly in said lower section and threaded into upper section, 105 dustguard recesses at both ends of said sections, and aligned recesses in said sections for securing said journal box to a truck frame.
- 75 20. In a journal box for railway trucks, in combination, upper and lower sections divided substantially on horizontal lines, means for securing said sections in cooperative relationship, said means including a bolt passing downwardly in said upper section and threaded into said lower section, and a bolt passing upwardly in said lower section and threaded into said upper section,

- and aligned dovetailed recesses in said sections.
21. In a journal box for railway trucks, in combination, upper and lower sections divided substantially on horizontal lines, means for securing said sections in cooperative relationship, said means including a bolt passing downwardly in said upper section and threaded into said lower section, and a bolt passing upwardly in said lower section and threaded into said upper section, and dustguard recesses and aligned dovetailed recesses in said sections.
22. A journal box comprising, in combination, complementary journal box sections adapted to be secured in cooperative relationship, dustguard recesses at both ends of said journal box, and aligned recesses in said sections for securing said journal box to a truck.
23. A journal box comprising, in combination, complementary journal box sections adapted to be secured in cooperative relationship, and a dovetailed recess for connecting the journal box to a truck frame.
24. A journal box comprising, in combination, complementary journal box sections adapted to be secured in cooperative
- relationship, a grease pocket located at one side of said journal box, and aligned recesses in said sections opposite said grease pocket for securing said journal box to a truck.
25. A journal box comprising, in combination, complementary journal box sections adapted to be secured in cooperative relationship dustguard recesses at both ends of said journal box and a dovetailed recess for connecting the journal box to a truck frame.
26. A journal box comprising, in combination, complementary journal box sections adapted to be secured in cooperative relationship, dustguard recesses at both ends of said journal box, a grease pocket located at one side of said journal box, and aligned recesses in said sections opposite said grease pocket for securing said journal box to a truck.

In testimony whereof I affix my signature, in the presence of two witnesses.

WILLIAM JUDSON SMITH.

Witnesses:

M. F. ERNST,
E. N. HOLSTROM.

Certificate of Correction.

It is hereby certified that in Letters Patent No. 1,405,168, granted January 31, 1922, upon the application of William Judson Smith, of St. Paul, Minnesota, for an improvement in "Trucks," errors appear in the printed specification requiring correction as follows: Page 3, line 7, strike out the words "secured at its upper end to a depending" and insert the words *provided on the horizontal portion and*; page 4, line 126, claim 6, for the words "side trussed" read *trussed side*; page 5, line 115, claim 19, before the word "upper" insert the word *said*; and that the said Letters Patent should be read with these corrections therein that the same may conform to the record of the case in the Patent Office.

Signed and sealed this 7th day of March, A. D., 1922.

[SEAL.]

WM. A. KINNAN,

Acting Commissioner of Patents.
